INFLATABLE WIG STAND

Paul Belokin, Jr., Berwyn, Ill., assignor to The Tel-E-Medic Company, Chicago, Ill., a firm composed of Norman Schwartz, M.D., and Natalie Pels Schwartz

Filed Apr. 24, 1967, Ser. No. 6,795

Term of patent 14 years

(Cl. D80—8)

FIG. 1 is a top plan view of an inflatable wig stand showing my new design in a collapsed condition.

FIG. 2 is a side elevational view of FIG. 1.

FIG. 3 is a bottom plan view of FIG. 1.

FIG. 4 is a perspective view of my inflatable wig stand in a partly open position; and

FIG. 5 is a side elevational view of my inflatable wig stand in an erected position.

The dominant features of my design are those portions shown in full lines.

I claim:

The ornamental design for an inflatable wig stand, substantially as shown and described.
